US00D549594S

(12) **United States Design Patent** (10) **Patent No.:** **US D549,594 S**
(45) **Date of Patent:** **** Aug. 28, 2007**

(54) **SIDE ACCESS FLEXIBLE PACKAGE**

(76) Inventor: **Mark Steele**, 1007 Lexington Ave.
North, New Prague, MN (US) 56071

(**) Term: **14 Years**

(21) Appl. No.: **29/254,969**

(22) Filed: **Mar. 2, 2006**

Related U.S. Application Data

(63) Continuation of application No. 10/396,295, filed on Mar.
25, 2003, now Pat. No. 7,040,810.

(51) **LOC (8) Cl. 09-05**

(52) **U.S. Cl. D9/707**

(57) **CLAIM**

I claim the ornamental design for side access flexible
package, as shown and described.

DESCRIPTION

FIG. 1 is a front perspective view of a side access flexible
package according to a first embodiment of the invention.
FIG. 2 is a front perspective view of an opened side access
flexible package according to the first embodiment of the
invention.

FIG. 3 is a front perspective view of a side access flexible
package according to the first embodiment of the invention.
FIG. 4 is a front perspective view of an opened side access
flexible package according to the first embodiment of the
invention.

FIG. 5 is a front perspective view of a side access flexible
package according to a second embodiment of the invention;
and,

FIG. 6 is a front perspective view of an opened side access
flexible package according to the second embodiment of the
invention.

The broken lines are for illustrative purposes only and form
no part of the claimed design.

The portions not shown in the above figures are not claimed
as part of the invention.
